UNITED STATES PATENT OFFICE.

HERBERT HAID, OF SALEM, OREGON, ASSIGNOR, BY MESNE ASSIGNMENTS, TO
PRESSSTEEL ENGINEERING CORPORATION, A CORPORATION OF NEW YORK.

VISIBLE CARD RECORD.

Application filed March 28, 1924. Serial No. 702,671.

This invention relates to new and useful improvements in visible card records.

In endeavoring to develop a visible card record, a person encounters many problems which must be overcome before the device truly can be termed practical. The device must be easy to operate, light in weight, and compact in structure. A large number of cards must be arranged in such a manner that their bulk will be entirely distributed over the entire available space and this bulk must be minimized as much as possible. It must be possible to quickly increase or decrease the number of cards, or accounts should the device be used as a ledger or credit record, and yet maintain the alphabetical arrangement of the same. It, also, must be possible to have more than one card in any individual account or division and these additional cards must be as accessible as the front or visible ones. When a card is removed from the carrier, there should be some means for easily determining the place from which the card was taken so that it may be quickly and properly returned and, furthermore, there should be some way of determining if any cards have been taken out of the carrier and not returned. The cards must be held by the carrier in such a manner that both sides or faces may be viewed and, last but not least, the cards must be capable of being easily removed or replaced and they must be suitable for being passed through a typewriting or bookkeeping machine. There are still many other problems that might be enumerated, but I believe the above noted ones will be sufficient for properly setting forth the difficulties encountered.

I am well aware of the fact that this field of work has been entered before, but after personally handling quite a number of the systems now on the market and after examining the patented art available to the public, I am of the opinion that, so far, a visible card record has not been developed that will overcome all of the problems noted above.

There has been considerable work done in this art on the idea of employing an element, usually in the form of a metallic tube or rod, which acts in a similar manner to a hinge pintle for allowing the card carried thereby to be pivoted for permitting both faces or sides of the same to be viewed. This form has its disadvantages, however, in that

such tubes or rods add to the bulk and necessarily the weight of the device and cause a piling up or bulging at the fulcrum lines of the cards. Also, in view of the fact that the cards are usually clamped to these tubes or rods or the rods are laced through apertures formed in the cards, it is practically impossible to provide more than one card for any individual account or division and have all of such cards accessible. This is due to the fact that the cards are bound together in such a manner that they must be pivoted as a whole or, in other words, each of the cards cannot be pivoted separately. In this form, when a card is removed from the carrier, the tube or rod attached thereto is usually removed with the same. This removal of the tube or rod with a card, should the remaining cards in the carrier be disturbed or shifted by any handling of the carrier or by a clerk examining any of these other cards, also destroys all signs of the place from which the removed card was taken.

Another line of development in this art has been to employ a master card or envelope within which the record card is placed. These master cards or envelopes are usually secured to a carrier by means of the aforementioned tubes or rods or the master card is sometimes provided with a binding strip hingedly carried by one border thereof. In the devices employing binding strips, the said strips are usually secured to the carrier by being clamped between blocks which will hold the strips against movement and the master cards may be pivoted upon their hinge lines for permitting the underneath record cards to be seen. From the objections noted in connection with the first form referred to, it readily will be seen that this latter form is even more cumbersome and bulky than that one, for, the master cards or envelopes add greatly to the volume of the record and when considered with the tubes, rods, or clamping blocks, it will be apparent that the record cards form but a small portion of this volume. Another objection to this form is that the record card must generally be separated from the master card or envelope before both sides of the former may be used. Of course, when the master cards are provided with hinged tubes or rods, the objections noted in connection

with first form are all applicable. If the clamping blocks are employed for holding the binding strips of the master cards against movement, the permanent removal of 5 a record card with its master card, will loosen the remaining clamping blocks and binding strips unless additional means is employed for binding or wedging all of these blocks and strips together. Such a means 10 will naturally add to the weight of the device and the cost of manufacturing the same and, for these reasons, is objectionable.

I am, also, aware of other forms where- 15 in master cards are employed and interlock- ingly connected together in a suitable manner for producing the visible feature com- 20 mon to all such devices, to wit: the expos- 25 ing of a strip along the top edge of the card. This form of device, however, may only be used as an index for the master cards cannot be freely pivoted, but can only be flexed or bent slightly for providing a better view of the entire front face of any particular index card. Considerable diffi- 30 culty is also encountered in adding new cards or taking out old ones in this form on account of the manner of interlocking connecting the adjacent master card.

There is still one more popular form of 35 development which consists in providing a carrier with a central, longitudinally ex- 40 tends rail to which the record cards are locked by means of spaced, opposed ears or lugs carried by the lower portions of the cards. This form is objectionable in that the cards cannot be freely pivoted for per- 45 mitting an unobstructed view of either side of any of the same. For this reason, this form is only suitable for use as an index.

40 It is now believed that the most common forms of visible records or indices now on the market or disclosed in the art have been referred to and some of their faults pointed out.

45 It is the primary object of this invention to provide a device which may be successfully employed for handling and displaying alphabetically arranged cards for keeping all kinds of record systems.

50 A further object of the invention is to provide a device of the above noted type which is easy to operate, light in weight, compact, and one wherein simplicity of construction plays an important part.

55 A further object of the invention is to provide a visible record wherein a large number of cards may be arranged in a limited space in such a manner that their bulk will be evenly distributed over such 60 available space and this bulk will be mini- 65 mized to the utmost.

A further object of the invention is to provide means for permitting all of the record cards to be freely and easily pivoted 70 for entirely exposing either face thereof

and such pivoting means will not cause a piling up or bulging to occur at the fulcrum points or lines of the cards.

A still further object of the invention is to permit new cards to be added and old 75 cards to be removed thereby permitting ex- 80 pansion and contraction of the record quickly and easily and yet maintaining the alphabetical arrangement of the same. Also, to 85 permit the employing of more than one card 90 in a division or account and yet allow all of these cards to be independently pivoted for entirely exposing either face of the same.

Another object of the invention is to so 95 construct the device that a card may be temporarily removed from the carrier or 100 tray and its place or position will not be lost regardless of how much handling the carrier receives while the card is out and 105 the maintaining of its place or position will provide a gap or vacancy that will indicate the absence of a card whereby the same 110 may be traced and returned.

Still another object of the invention is 115 to provide a record card which may be easily and safely passed through a type- 120 writing or bookkeeping machine.

Other objects and advantages of the in- 125 vention will be apparent during the course 130 of the following description.

In the accompanying drawings forming 135 a part of this specification and in which like numerals are employed to designate 140 like parts throughout the same,

Figure 1 is a top plan view of the visible record embodying this invention and shows 145 all of the record cards in their normal posi- 150 tions.

Figure 2 is a similar view to Fig. 1, but 155 illustrates a portion of the record cards flipped or turned over for exposing the entire front face of one card and the entire back face of another card,

Figure 3 is a top plan view of the visible record embodying this invention shown with 160 the binders moved out of their locking or 165 closed position for better illustrating the arrangement and provision of the bearings 170 which are employed for pivotally support- 175 ing the record cards,

Figure 4 is a longitudinal sectional view 180 taken upon line IV—IV of Fig. 3 and illus- 185 trates the manner in which the record cards engage each other while all of the same are 190 in their normal positions,

Figure 4^a is a fragmentary longitudinal 195 sectional view of the device embodying this 200 invention and shows four record cards in 205 their normal positions in full lines and in 210 their relative positions while being flipped or turned over, in dotted lines,

Figure 5 is a transverse sectional view 215 taken upon line V—V of Fig. 1 and illus- 220 trates in detail the manner of pivotally con- 225

necting the binders to the body portion or tray of the device,

Figure 6 is a transverse sectional view taken upon line VI—VI of Fig. 1 and illustrates the journal portions of one of the record cards properly arranged in respect to the bearings which permit pivoting of the cards,

Figure 7 shows a fragmentary longitudinal sectional view and illustrates the adaptability of the device for handling more than one record card in any particular division or account,

Figure 8 is a fragmentary sectional view and illustrates the method employed for securing stops to the side flanges or bearing-carrying rails of the tray,

Figure 9 is a perspective view of one of the bearings employed in connection with this device,

Figure 10 is a fragmentary perspective view of one of the record cards and illustrates the formation of one of the journals carried thereby,

Figure 11 is a fragmentary sectional view of the tray and illustrates a modification which consists of forming a longitudinally extending bead on the flange or bearing-carrying rail of the tray and a complementary groove in the type of bearing adapted to be employed therewith,

Figure 12 illustrates a fragmentary perspective view of the tray with the modified form of flange or bearing-carrying rail, and

Figure 13 is a perspective view of the modified form of bearing employed in connection with the type of rail illustrated in Fig. 12.

In the drawings, wherein for the purpose of illustration is shown a preferred embodiment of this invention, the numeral 5 designates a tray or carrier which is of substantially rectangular formation in plan view and may be formed of any suitable light material. This tray is provided with an upturned flange 6 at one end and an inwardly turned flange 7 at its other end, this flange 7 preferably being bent into engagement with or lying closely upon the top face of the tray 5. The opposite longitudinal edges of this tray are provided with upturned flanges 8 which act as bearing-carrying rails.

Illustrated in detail in Fig. 9 is a bearing 9 which is preferably formed of metal of relatively small gage, it being understood, however, that this bearing may be formed of celluloid or other similar thin material. This bearing consists of top and bottom walls 10 and 11 and side walls 12, while one transverse edge of the top wall 10 is provided with an integrally formed depending supporting clip 13. It is to be understood that this bearing may be formed by a molding operation or it may be stamped from a

sheet of suitable material and bent into proper form with the seams brazed or welded.

In Figs. 3, 4, 4^a, 5 and 9 the flanges or rails 8 of the tray 5 are illustrated as being provided with a plurality of these bearings 9 positioned thereupon. It is to be understood that the supporting clips 13 of these bearings are to be positioned outwardly of the rails 8 while the remaining body portions of the bearings are to be positioned inwardly of these rails and with their open ends arranged in transverse, axially alined pairs. For the purpose of maintaining these bearings 9 carried by the opposite rails 8 in axial alinement and for maintaining the outer faces of the side walls 12 of adjacent bearings in engagement with each other, the rails 8 are provided with fixed stops 14. In Fig. 8 there is illustrated one of these stops 14 and the manner of securing the same to the rail 8 is clearly shown. These stops 14 each consist of a U-shaped portion 15 which carries a laterally projecting lug 16. The U-shaped portion 15 of this stop is illustrated as being secured to the rail 8 by the stamped indentures 17.

Referring to the various figures and particularly to Fig. 10, it will be seen that there has been provided record cards 18 which are formed with laterally projecting tongues 19 with the tongues on each card arranged in axial alinement with each other and having their axes positioned upon a plane extending in parallelism with the bottom edge 18^a of the card and slightly spaced therefrom, also, that this bottom edge 18^a forms one edge of the tongues 19. The opposite longitudinal edge of each tongue 19 forms a continuation of the side edge 18^b of the record card and is provided with the arcuately formed point of connection 20. It will be clearly seen that these tongues 19 are formed integrally with the body portion of the card 18 and that the arcuately formed web 20 will act as a reinforcement for the said tongue.

In Figs. 1 to 3 inclusive the cards 18 are shown in position and have their tongues 19 arranged in axially alined bearings carried by the opposite rails 8. In Fig. 4^a there are illustrated four cards 18 which are shown in full lines in their normal positions and in dotted lines in positions assumed thereby while being flipped or turned over. It will be seen that these tongues 19 act as journals when received within the bearings 9 for permitting the cards 18 to be pivoted.

For the purpose of retaining these bearings 9 in their proper positions upon the rails 8 and yet to permit the removal of the same when desired, a channel-shaped binder 21 has been provided for each longitudinal edge of the tray 5 and is pivotally connected, in proximity to the point of connection 125

between the outer end flange 6 and a rail 8, to the tray 5 by means of the pin 22 which is provided with a spacer block 23 that maintains the upper flange of this channel-shaped binder on a plane suitable for causing the same, when swung into its closed position, to just clear the outer face of the top wall 10 of each of the bearings 9 intended to be retained in position by the said binder. By inspecting Figs. 5 and 6, it will be seen that the bottom flange of this channel-shaped binder 21 frictionally engages the bottom face of the tray 5. Due to the frictional engagement of the opposite flanges of the binder 21 with the top wall 10 of the bearings and the bottom wall of the tray 5, the said binders will be retained in their closed or locking position without requiring any additional fastening means.

In Fig. 4 there is illustrated the tray in section and a multiplicity of record cards in their normal positions. In Fig. 4^a there are only shown four record cards in position. It will be noted that in this latter figure the various cards are illustrated as having their adjacent faces flushly engaging each other and with each card positioned upon a slightly inclined plane with the inclinations occurring from the outer edge to the inner edge of each card. The tongues or journals 19 on the cards are illustrated as being spaced from the bottom walls 11 of the bearings distances equal to the thicknesses of the cards positioned therebeneath. It will be apparent that should the record cards maintain the positions illustrated in Fig. 4^a, when a multiplicity of cards were positioned within a tray, the tongues or journals would pile up until they would bind against the top walls of the bearings. Fig. 4, however, illustrates the proper relative positions of the cards when a multiplicity is provided. It will be noted in this figure that the cards are inclined in an opposite direction to the inclination illustrated in Fig. 4^a. In other words, the journal-carrying portions or edges of the cards are all illustrated as being in engagement with the bottom walls of the bearings. These journals are maintained in engagement with the bottom walls of the bearings by the weight of the portions of the cards positioned in vertical alignment with the said journals. Therefore, when a multiplicity of cards are carried by the tray the portions of the same carrying the journals will not bulge up or pile up for causing binding against the top walls of the bearings.

In Fig. 7 there is illustrated the adaptability of the device for handling more than one card in any one pair of axially aligned bearings. With this construction there may be provided several cards in any one division or in a position to be carried by any pair of aligned bearings and all of these

cards may be pivoted together or any desired lesser number of cards than the total number may be pivoted together, thereby making it possible for viewing both sides of any of these plurality of cards carried by any pair of aligned bearings.

It will be apparent that with the form of clip designated as 13 in Fig. 9, a binding member such as that designated by the numeral 21 in Fig. 3 is necessary for retaining the bearings in their proper positions upon the carrying rails 8. For the purpose of permitting the elimination of the binder 21, there is illustrated in Figs. 11 to 13 inclusive a modified form of rail which is designated by the numeral 8^a. This rail is provided with a longitudinally extending bead 24 which is arranged with its raised portion projecting outwardly of the tray. In Fig. 13 there is illustrated a journal 9^a having a clip 13^a which is formed with a transversely extending groove 24^a. In Fig. 11 the bearing 9^a is illustrated as being properly positioned upon the tray with the groove 24^a in position for slidably engaging the bead 24. It is intended that this bead and groove formation shall retain the bearings in engagement with the rails without necessitating the provision of a binder.

In Figs. 1 and 2 the trays are illustrated with a multiplicity of cards positioned therein. In Fig. 1 the cards 18 are shown in their normal position and it will be seen that the cards are arranged in respect to each other for maintaining visible a strip 25 at the upper longitudinal edge portion of each card. These strips maintained in view are adapted for receiving persons' names or the like. When this visible record is employed as a bookkeeping ledger, the cards may be ruled in a similar manner to that illustrated in Fig. 2. The back face of each card is preferably provided with an unruled strip at the outer edge portion thereof, as designated by the numeral 25^a upon which the same name may be printed that appears upon the strip 25 of the same card. It will be apparent, by inspecting the pivoted or turned-over cards at the lower portion of the tray illustrated in Fig. 2, that the rear face of each card may also be employed for keeping records and may be ruled in a similar manner to the front face.

It is now believed that the operation of the device embodying this invention will be clearly understood from the above detail description. It will be apparent that the tray may be first put in operation with a desired number of unoccupied pairs of bearings positioned, as illustrated in Fig. 3, at the one end of the tray 5. With the record in operation, it is a very easy matter to insert or withdraw cards from the record or in other words withdraw the tongues or journals from the bearings. This may be

accomplished by slightly bending or flexing the card upon a transversely extending line which will shorten its length for withdrawing the journals from the open ends of the bearings. When a card has been removed in this manner, it will be apparent that a pair of axially aligned bearings will be minus a card and there will be created a vacancy or gap in the exposed strips 25. This vacancy or gap will aid a person to properly return the removed card to its designated place. This vacancy will also give warning of the absence of a card and this card may be traced and returned to its proper tray. 15 Should a person desire to permanently withdraw a card, the same may be disconnected from its pair of bearings in the manner just described and after the binders 21 have been pivoted into the positions illustrated in Fig. 3, the particular pair of bearings that formerly carried the permanently removed card may be lifted upwardly off of the carrying rails 8. The remaining bearings with their record cards may then be shifted 20 longitudinally along the tray and the removed pair of bearings may be inserted between the last pair of occupied bearings and the first pair of unoccupied bearings. It will also be apparent that should a new 25 card be made out that must be placed in a tray in alphabetical arrangement with the cards already carried by that tray, a pair of unoccupied bearings may be removed from the rails 8 and the record cards with 30 their bearings shifted for providing a space on each rail 8 at the proper place of insertion of the new card. These unoccupied bearings may then be placed upon the rails in these vacant spaces and the new card connected to these bearings.

It will be apparent that the journals or tongues 19 carried by each card will eliminate the necessity of providing any additional element, such as a rod or clamping tube for carrying the cards. It has been discovered by actual use that these record cards may be successfully handled without any great danger of tearing off the journals or tongues 19. However, the tongues, or 45 journals 19 may be dipped in a suitable preparation for stiffening or toughening the same and all danger of tearing will then be eliminated.

It is to be understood that the forms of this invention herewith shown and described are to be taken as preferred examples of the same, and that various changes in the shape, size, and arrangement of parts may be resorted to without departing from the spirit 55 of the invention or the scope of the subjoined claims.

Having thus described the invention, I claim:—

1. In a device of the type described, a

portable support, a multiplicity of record 65 cards, a pair of journals formed integrally with each of said cards, and means removably carried by said support for receiving said journals to permit pivoting of said cards. 70

2. In a device of the type described, a portable support, a multiplicity of record cards, a pair of journals integrally formed with each of said cards, and independently removable means carried by said support 75 for receiving the said journals to permit pivoting of said cards.

3. In a device of the type described, a support, a multiplicity of bearings adjustably carried by said support, a multiplicity of 80 record cards, and means formed integrally with said cards and removably received in said bearings while carried by said support for pivotally supporting the cards. 85

4. In a device of the type described, a support, a plurality of independent bearings carried by said support and adjustable by being slidably moved therealong, a multiplicity of record cards, and means formed 90 integrally with said cards and removably received in said bearings while carried by said support for pivotally supporting the cards.

5. In a device of the type described, a support, a multiplicity of removable bearings 95 carried by said support, a multiplicity of record cards, and means formed integrally with said cards and received in said bearings for pivotally supporting the former.

6. In a device of the type described, a support, a multiplicity of independently removable bearings carried by said support, a multiplicity of record cards, and means formed 100 integrally with said cards and received in said bearings for pivotally supporting the former. 105

7. In a device of the type described, a support, a pair of axially aligned bearings removably carried by said support, a record card, and means formed integrally with said card and received in said bearings for pivotally supporting the former. 110

8. In a device of the type described, a support, a pair of axially aligned bearings independently removably carried by said support, a record card, and means formed 115 integrally with said card and received in said bearings for pivotally supporting the former.

9. In a device of the type described, a support, a pair of spaced flanges carried by said support, a series of bearing elements removably supported by each flange, and a plurality of record cards pivotally carried by said 120 bearings. 125

10. In a device of the type described, a support, a pair of spaced flanges carried by said support, a series of bearing elements

- removably supported by each flange, and a record card pivotally connected to one of said bearings on each of said flanges.
11. In a device of the type described, a support, a pair of spaced flanges carried by said support, a series of bearing elements removably supported by each flange, each of the bearings carried by one of said flanges being in axial alinement with a bearing carried by the other flange, and a record card pivotally carried by each pair of axially alined bearings.
12. In a device of the type described, a support, a pair of spaced rails carried by said support, a series of removable bearings engaging over the edge of each rail, and a plurality of record cards pivotally carried by said bearings.
13. In a device of the type described, a support, a pair of spaced rails carried by said support, a series of independently removable bearings engaging over the edge of each rail, and a plurality of record cards pivotally carried by said bearings.
14. In a device of the type described, a support, a pair of spaced rails carried by said support, a series of independently removable bearings engaging over the edge of and slidably mounted on each rail, and a plurality of record cards pivotally carried by said bearings.
15. In a device of the type described, a support, a pair of spaced flanges carried by said support, a series of bearings removably carried by said flanges, means for preventing accidental displacement of said bearings, and a plurality of record cards pivotally carried by said bearings.
16. In a device of the type described, a support, a pair of spaced flanges carried by said support, a series of bearings independently removably carried by each flange, means for preventing accidental displacement of said bearings, and a plurality of record cards pivotally carried by said bearings.
17. In a device of the type described, a support, a pair of spaced flanges carried by said support, a series of bearings independently removably carried by each flange, means for preventing accidental displacement of said bearings, a plurality of record cards, and means carried by each of said cards and received within a pair of bearings for pivotally carrying said cards.
18. In a device of the type described, a support, a pair of spaced flanges carried by said support, a series of bearings removably carried by each flange, means for preventing accidental displacement of said bearings, a multiplicity of record cards, and means formed integrally with said cards and received within said bearings for pivotally supporting said cards.
19. In a device of the type described, a support, an angularly extending flange carried by each longitudinal edge of said support, a series of bearings engaging over the edge of each of said flanges, and a plurality of record cards pivotally carried by said bearings.
20. In a device of the type described, a portable support, an integrally formed angularly extending flange carried by each longitudinal edge of said support, a series of bearings removably carried by each flange, means for preventing accidental displacement of said bearings, and a plurality of record cards pivotally carried by said bearings.
21. In a device of the type described, a portable support, an angularly extending flange carried by each longitudinal edge of said support, a series of bearings independently removably carried by each of said flanges, means for preventing accidental displacement of said bearings, a multiplicity of record cards, and means carried by said cards and received within said bearings for pivotally supporting said cards.
22. In a device of the type described, a support, a pair of spaced flanges carried by said support, a series of bearings carried by each of said flanges, and a multiplicity of record cards pivotally carried by said bearings, said bearings each consisting of a hollow body portion and a clip portion carried by said body portion and adapted to engage said flange.
23. In a device of the type described, a support, a pair of spaced flanges carried by said support, a series of bearings engaging over the edge of each flange, a multiplicity of record cards, and means carried by said cards and received in said bearings for pivotally supporting the former, said means comprising axially alined tongues carried by opposite edges of said cards.
24. In a device of the type described, a support, a pair of spaced rails carried by said support and provided with a pair of bearings having journal-receiving slots elongated in a direction perpendicular to the support, and a plurality of record cards having journals mounted in said bearings for rotation therein and for movement toward and from the support.
25. In a device of the type described, a support, a pair of spaced rails carried by said support, a series of removable bearings suspended from each rail and each having a bearing slot elongated in a direction perpendicular to the support, and a plurality of record cards pivotally carried by said bearings and movable in the bearings toward and from the support.

In testimony whereof I affix my signature.

HERBERT HAID
